FIG. 2.

FIG. 3.

UNITED STATES PATENT OFFICE

HENRY BLACKMAN, OF NEW YORK, N. Y.

VENTILATING TUNNELS.

No. 893,049.

Specification of Letters Patent.

Patented July 14, 1908.

Application filed December 20, 1906. Serial No. 348,744.

To all whom it may concern:

Be it known that I, HENRY BLACKMAN, a citizen of the United States, residing in the borough of Manhattan, city, county, and State of New York, have invented certain new and useful Improvements in Ventilating Tunnels, of which the following is a specification.

In my application for patent for improvements in ventilating and purifying the atmosphere of tunnels (filed April 16, 1906, No. 311,938), I have described a structure in which the atmosphere is purified by providing openings at points intermediate between numerous entrances in a subway, the foul air (or smoke in case of fire) being withdrawn at such intermediate points so as to maintain a current of air entering the tunnel or subway entrances in fresh condition, and passing to the intermediate points, and thence out.

The present application is intended to cover broadly ventilation by the use of such openings, being based on a structure embodying the same generic idea, but presenting certain advantages in the separate features of construction; the various improvements in detail being defined in the claims hereinafter and described in detail in connection with the embodiment of the invention illustrated in the accompanying drawings in which

Figure 1 is a longitudinal section through a subway taken approximately on the line 1—1 of Fig. 2, and Fig. 2 is a transverse section taken approximately on the line 2—2 of Fig. 1. Fig. 3 is a transverse section on the line 3—3 of Fig. 1.

At the point at which the air is to be exhausted, there is provided a chamber at the side of the tunnel or subway, and the air from the tunnel is passed into this chamber and thence out, escaping either at the sidewalk or other surface immediately overhead, or through chimneys or other special vents provided for the purpose. This special chamber at the side of the tunnel, and communicating with the air within, is capable of a number of uses. A valuable function of such a chamber is to provide a large outlet for the air passing out of the tunnel so that this air, when exhausted through a sidewalk, may be made to flow at a very moderate velocity to avoid any disagreeable effect upon persons passing over the pavement. This advantageous result is independent of

the means provided for causing the passage of the air out of the tunnel. For causing such an outflow of the air from the tunnel, it is preferable to employ a fan or similar device and the side chamber provides a convenient space for locating one or more fans with their inlets communicating with the tunnel and their outlets with the chamber. It sometimes happens that for various causes trains are stopped in such tunnels at points between the entrances and for so long a time that passengers are compelled to get out of the trains and walk to the nearest entrance. This is a dangerous matter by reason of the darkness, the possible passing trains, and the liability to injury from contact with electric conductors where such are employed. A very important utility in the said chambers referred to is the possibility of using them as emergency exits and thus bringing the points at which passengers can leave the tunnel much nearer to each other than where only the entrances can be used for such purpose. The side chambers may also be arranged to form traps, below the point at which the air passes out from the tunnel so as to catch any water which might enter at the point of final discharge of the air, and carry it off to the sewer. The chambers may also carry screens for retarding the velocity of outflow of air, and for preventing or restricting the entrance of dirt, and may carry fire hose and various other devices.

Referring to the drawings, the tunnel or subway proper is indicated at A and along side of it is a chamber B communicating with the tunnel through any desired number of openings C and communicating with the outer atmosphere through the sidewalk D or any other part of the overhead pavement. A chamber of this sort will ventilate the tunnel to a considerable extent without any other apparatus, the passage of trains at the point where the openings C are arranged causing a certain outflow of air through such openings, which outflow is only partially balanced by the inflow after the train passes these points. Also the difference in temperature between the air below and that above will ordinarily effect considerable ventilation.

Valves are provided to serve to cut off communication between the tunnel and the side chamber whenever desired. Swinging valves or dampers E may be used for this

purpose, mounted on shafts F, operated by worm gears G and hand wheels H, or by any other suitable means preferably accessible from within the chamber B. For example 5 the gearing and hand wheels may be arranged in recesses J formed in the tunnel wall K for the purpose.

Notwithstanding the withdrawal of the bad air from the tunnel by reason of the passage of trains and by natural circulation due 10 to the differences of temperature, it is generally advisable to employ a fan or similar additional withdrawing means and such fan may be conveniently located within the chamber B and immediately at the outlet 15 end of each of the openings C. For example propeller fans L operated by electric motors M may be mounted upon brackets N attached to a lining O of said openings. The 20 motor may be controlled by a switch P. The air from the fans L is discharged into a series of inner chambers Q communicating through screen doors R, and one side of which is formed by the tunnel wall K, and the top 25 of which is closed, the outer side and bottom, however, being formed of gratings S and T respectively through which the air escapes in full volume and without substantial back pressure upon the fan but at a very much 30 slower velocity because of the much greater area or aggregate cross-section of the several passages. The air after escaping from the inner chambers Q, passes into the main chamber and out through a grating U forming the 35 sidewalk or pavement and arranged with oblique openings to deflect the air toward the curb. One or more ladders V may be provided at suitable points and passing through the floor or grating T with or without a trap 40 door for obtaining access to the hand wheels H or other devices within the inner chamber. There may also be provided within this chamber a pair of electric indicators W and X and one or more electric lamps Y preferably 45 arranged near the indicators to facilitate the reading thereof. These indicators may be for measuring the current used in the fans or in the propelling of trains, and the side chamber may carry various other apparatus 50 for investigating or controlling the current. The upper wall of the inner chambers Q is preferably a trough Z having a grating a for a cover, and adapted to receive water coming in through the sidewalk grating U, the water 55 being carried off from the trough Z by means of a pipe b leading through a trap of the usual sort to the sewer c. For preventing choking of the trough Z or the pipe b, one or more dirt catchers are provided, each consisting of 60 a coarse screen d above a fine screen e, both screens being readily removable upward to facilitate cleaning. The grating U, it will be understood, is also removable, preferably in short sections.

65 The outlet openings C from the tunnel and

the apparatus connected therewith are preferably located at a point adjacent to the roof of the tunnel so as to take out the warmest air of the tunnel. Where the chamber B is to be used as an emergency exit for passengers, a door f is arranged preferably on a level with the floor of the tunnel and opening outward from the tunnel so that the pressure of air in the chamber B will tend to close the door tightly and so prevent the escape of 70 such air back into the tunnel. The door f leads through an opening or passageway g preferably into a lower chamber k with a grating side wall h, and a grating floor j similar to the upper chambers Q and for a 80 similar purpose. The main chamber B preferably extends below the grating j to form a pit l for the collection of water or debris of any sort, the water being pumped up by means of a pump m driven by a motor n, 85 controlled by a switch o, the water being discharged into the sewer c as shown. If the sewer is located as shown at c', below the bottom of the chamber l, then the water from this chamber may be siphoned off and the 90 water from the overhead trough Z may be led straight into this chamber through a pipe p, in which case, of course, the pump m and its motor will be omitted.

An emergency or fire hose q may be carried, 95 upon a bracket within the lower inner chamber k and connected with the street main r.

For providing access to the upper inner chambers Q and to the lowest chamber l, the ladder V runs down into the latter chamber 100 through the intermediate chamber k.

Exit from the chamber to the roadway overhead is provided by any suitably arranged ladder or preferably a stairway s leading up to any suitable trap door at the 105 street level and passing up alongside the side walls or gratings S and h of the inner chambers. For this purpose a door t is provided in the wall h of the lower chamber and in line with the door f of the tunnel, the door t being shown ajar in Fig. 2 for convenience of illustration, though ordinarily it will stand closed.

Ordinarily the electric conductors are arranged in conduits built into the wall K of the tunnel, such for example, as the conduits 115 u, and they may be arranged to run across the openings C as illustrated, for example, at v. Where there is not sufficient room for them, however, in the positions stated, or where it is not desired to run them across the 120 openings C, they may be depressed below the wall K or lifted above it as indicated respectively at w and x.

It will be understood that the chamber l, being merely a catch basin, need not extend 125 the entire length of the main chamber B. It may be considerably shorter as shown in Fig. 1. The inner chamber k also need only be of such length as to provide convenient access from the passage g through the tunnel wall 130

to the outer side of the chamber B where the stairway *t* is located, and the main chamber B and succession of inner chambers Q may be of less length than the sidewalk grating overhead.

In my other pending application above referred to there is disclosed in common with this application, the idea of ventilating tunnels or subways having passenger entrances at intervals by causing a flow of air longitudinally through the tunnel between the passenger entrances and points intermediate between such entrances, and preferably in the direction from the passenger entrances to the intermediate points so that passengers on entering the tunnel or subway will receive the immediate benefit of the freshest air. Such a structure is claimed broadly in this application, regardless of the means or arrangement employed for causing the circulation of air; the other application being limited to means for causing the circulation by withdrawing the air at the intermediate point or points.

The apparatus herein illustrated or any necessary part or modification thereof, may be located adjacent to the passenger entrances to exhaust the air at such points. Or the chamber described may be utilized for forcing the atmospheric air into the tunnel at points intermediate between the passenger stations causing a current which is necessarily discharged at the passenger stations. For this purpose the air forced in at the intermediate points may be cooled or heated according to the season of the year and the temperature of the outside air. The attenuating of the air, for example, may be performed in the side chamber before the air enters the tunnel. The air may likewise be disinfected in a similar way and at similar points and may be screened at the entrance to keep out the dirt and at the exit to break its velocity.

Various other modifications in detail and in the arrangement and combination of the

parts may be made by those skilled in the art without departure from the invention.

What I claim is:

1. A tunnel having an opening through an overhead roadway and a ventilating opening for the escape of air through the wall of the tunnel and communicating with said opening through the roadway, the opening through the roadway being larger than that through the tunnel wall, so that the velocity of the escaping air is lessened.

2. A tunnel having an opening through an overhead roadway and an opening for the escape of air through the wall of the tunnel in combination with a chamber between said openings, said chamber and opening through the roadway being of such size that the velocity of the air coming from the opening through the tunnel wall is lessened and it escapes more slowly through the overhead roadway.

3. A tunnel having a ventilating opening through its wall and means outside of the tunnel for compelling the air to escape into the outer atmosphere more slowly than it passes through said opening.

4. A tunnel having a ventilating opening through its wall, and a screen through which the air from said opening passes, the aggregate area of the openings through said screen being greater than the area of the current of air escaping through the opening in the wall of the tunnel.

5. A railway tunnel having a chamber open to the atmosphere and communicating with the tunnel at a point above the bottom of the chamber, so that such bottom forms a catch basin for water.

In witness whereof, I have hereunto signed my name in the presence of two subscribing witnesses.

HENRY BLACKMAN.
